OLEFIN ISOMERIZATION PROCESS

Howard L. Wilson, Raritan Township, Middlesex County, and Robert Drogan, Linden, N. J., assignors to Esso Research and Engineering Company, a corporation of Delaware

Application February 29, 1952, Serial No. 274,248

13 Claims. (Cl. 260—683.2)

The present invention relates to a process for isomerizing olefins and more particularly to the isomerization of terminally unsaturated higher molecular weight olefins. Mono-olefin hydrocarbons having the double bond at one end of the chain, such as mono substituted ethylenic alpha olefins having the general formula

wherein R is an alkyl group, are produced by cracking hydrocarbons and by various synthetic procedures. It is frequently desired to produce internally unsaturated olefins for use in high octane fuels, for making various chemical intermediates, for producing special types of olefin polymers and the like. The chief object of the present invention is to disclose an effective means for accomplishing olefin isomerization whereby double bond shifting and possibly other rearrangement of the molecule takes place.

In accordance with the present invention, high molecular weight alpha olefins are intimately contacted with alkali metal at an elevated temperature. After the desired degree of isomerization has taken place, alkali metal and undesirable reaction products are separated from the reaction mixture, and a product including internally unsaturated mono-olefins is recovered.

The discovery that alkali metals have the ability to catalyze the isomerization of high molecular weight olefins is completely unexpected since olefin isomerization usually involves acid conditions. The result is also unexpected since the alkali metal is specific for isomerizing olefins having at least 10 or more carbon atoms, olefins having a smaller number of carbon atoms being substantially unaffected.

The present invention will be better understood by reference to the sole figure of the drawing, taken in connection with the following description of a continuous method for carrying out olefin isomerization. Referring to the figure, an olefin feed prepared by means not shown is introduced into the system by means of line 11. The feed may for example have a boiling range of about 200° to 350° C. and will include substantial quantities of alpha olefins having from about 11 to 20 carbon atoms. A portion of the feed is charged by pump 12 through line 13 and line 14 to preheater 15. Another portion of the feed is passed to one of dispersion makeup drums 16 or 17 through lines 18 or 19 controlled, respectively, by valves 20 and 21. Each of the drums includes an agitating means, such as propellers 22 fixed to a shaft rotated by prime mover means not shown, whereby a high degree of shear is obtained.

Alkali metal is introduced into drums 16 or 17 through line 23 and branch lines 24 and 25 including, respectively, valves 26 and 27. The alkali metal is conveniently introduced as an "alkali metal sand" which is a coarse granulated suspension of the metal in an inert liquid medium, the metal having particle sizes as low as 2 mm. or lower. The metal suspension may also include a dis-

2

persing aid such as a high molecular weight fatty acid, carbon black, or the like.

The olefin feed and alkali metal are thoroughly agitated by the stirrer to form a concentrated dispersion or emulsion of the alkali metal in the feed. Conveniently the drums may be steam jacketed or heated by means not shown in order to prepare the dispersion at a temperature of about 100° to 130° C. or higher. In this manner the alkali metal will be dispersed as minute molten droplets suspended or emulsified in the hydrocarbon; with the use of a dispersing aid, an extremely stable suspension is prepared. This concentrate may contain as high as 10 to 50% of alkali metal, and will generally be sufficiently fluid for subsequent handling.

After dispersion has been prepared in one drum, it is passed through line 14 containing pump 28 by controlling valves 29 or 30. A similar dispersion may then be made in the other drum for subsequent use. The dispersion passing through line 14 is combined with olefin feed passing through line 13 in a proportion such that an alkali metal concentration of about 0.01 to 5.0 weight per cent, based on the olefins, is obtained. The mixture is heated to preheater 15 to a temperature in the range of about 175° to 350° C. and is then passed through line 31 into reaction zone 32. Zone 32 is conveniently surrounded by jacket 33 having an inlet 34 and outlet 35 through which a heating medium such as steam or the like may be passed to maintain reaction temperature.

The reaction zone includes an impeller 36 rotated through shaft 37 by a prime mover such as a motor 38. Impeller 36 is positioned at the lower end of draft tube 39, the draft tube being centrally disposed in reaction zone housing 32.

Reactants and catalyst introduced into zone 32 are forced by impeller 36 upwardly through draft tube 39 and are circulated downwardly through annular space 40 between the walls of the reactor and draft tube. A high degree of agitation is thus obtained, and the olefins are thoroughly contacted with the dispersed metal in order to obtain maximum utilization of the latter.

Reaction zone effluent is withdrawn at a constant rate through line 41 positioned in the top of zone 32 and is forced through pump 42 into the lower portion of soaker 43. The soaker likewise includes a draft tube 44 and an impeller 45 arranged to give good circulation and agitation during the soaking period. The soaker does not require heating. The contents of the soaker are maintained near the reaction temperature by the specific heat available. This gives additional residence time at somewhat 50 below the reactor temperature but sufficiently high to complete the isomerization reaction.

Effluent is passed from zone 43 by line 46 through a heat exchanger or chiller 47 wherein it may be further cooled. The cooled effluent is then passed through line 48 containing pump 49 into one of a plurality of filter beds 50 or 51 by means of branch lines 52 or 53 containing valves 54 and 55, respectively. The filter beds may be provided with a suitable filtering material, such as diatomaceous earth or the like, one filter bed being used while the other is being regenerated or refilled with fresh clay. Alkali metal, sludge and any other undesirable reaction products or unreacted solids are removed from the treated hydrocarbon during the filtering step. The product containing isomerized olefins is withdrawn 65 through line 56.

In order to improve the utilization of alkali metal and to speed the isomerization reaction, it is preferred to add an activator such as aliphatic alcohol or the like to the reactants. This may be done by charging, for example, 70 isopropyl alcohol through line 9 containing pump 10 into line 13, wherein the alcohol is combined with the olefin feed.

The product withdrawn through line 56 may be charged to a distillation means not shown for separation or may be charged to other purification means. It may be desired to blend the metal-free product directly into high boiling aviation safety fuels or the like in order to improve the octane rating thereof. It will be obvious to the skilled workman that the subsequent treating of the isomerized product will depend upon its ultimate use.

The temperature at which the isomerization reaction is carried out will generally be above about 150° C. and should be below the incipient cracking temperature of the hydrocarbons (about 425° C. or higher), a preferred range being about 175° to 350° C. It is preferred to carry out the operation under pressures sufficiently high to keep the hydrocarbons in the liquid phase. Reaction times are generally not critical and will depend to a large extent on the temperature as well as the size of the dispersed alkali metal particles.

The rate at which the reaction proceeds will be controlled to a large extent by the metal surface available. Obviously, dispersed particles having average diameters as low as about 0.001 to 10 microns will have many times the surface area of the same concentration of particles having diameters as high as 100 to 1,000 microns. For these reasons, it is preferred that the alkali metal be in finely divided form during the contacting step. Finely dispersed particles having sizes below about 50 to 1000 microns in average diameter are generally more useful than larger sized particles.

The particle size will also influence the concentration of alkali metal needed to effect a desired conversion. Under some conditions, as low as 0.01 to 0.1 weight percent alkali metal, based on the olefin in the feed, will be sufficient providing finely sized dispersed particles are used. On the other hand, up to 10 or 20 weight percent alkali metal may be desired when using larger particles. A generally useful range is about 0.25 to 5.0 weight percent of the alkali metal based on the olefins. Under these conditions, contact times may vary from below about 5 minutes up to 5 or 10 hours, although about 30 minutes to 3 hours will generally be sufficient.

The alkali metal employed in the practice of the present invention is preferably sodium although potassium, lithium, mixtures of alkali metals, or certain active alloys containing alkali metals are useful. As pointed out above, the isomerization reaction is greatly facilitated by using alkali metal in the dispersed form, the particles preferably being molten although solid particles may be used successfully. Suitable dispersions may be obtained by utilizing high speed agitators, colloid mills, homogenizers and the like for the thoroughly dispersing molten metal in a suitable vehicle.

In order to maintain the metal catalyst in the dispersed state, it is desired to employ a dispersing agent. Organic compounds which are soluble in the hydrocarbon medium are preferred. Such materials include the higher molecular weight fatty acids or their soluble metal soaps. Carbon black may also be used for this purpose. Generally an amount of dispersing aid in the range of 0.5 to 5.0 weight percent, based on the alkali metal will be adequate.

It is also preferred to have an organic activator present during the isomerization step. These materials help to keep the surface of the alkali metal clean and may in some other way activate and accelerate the reaction. In the range of about 1 to 30 mol percent, preferably 5 to 15 mol percent, of activator, based on the alkali metal, will generally be sufficient, although smaller or larger amounts may be useful in some cases. The most suitable activators are organic compounds consisting of carbon, hydrogen and oxygen, and termed herein oxy hydrocarbons, having below about 10 carbon atoms. Particularly preferred are such compounds containing an active hydrogen such as fatty acids, alcohols, polyhydroxy alcohols such as glycols, alcohol-ethers, phenols, malonic esters, etc. Other compounds such as ketones, ethers and the like may be

used. Alcohols such as ethyl, propyl, butyl and particularly the secondary and tertiary alcohols such as isopropyl, secondary and tertiary butyl alcohols, etc., are useful. Other specific activators include ethylene glycol, propylene glycol, 1,2-butanediol, erythritol, diethylene glycol, phenol, cresol, acetone, methyl ethyl ketone, methyl isobutyl ketone, ethyl ether, isobutyl ether, etc.

The feed stocks used in the practice of the present invention may be substantially pure individual or mixed alpha-olefins having at least about 10 carbon atoms. It is generally preferred that the olefins contain below about 25 carbon atoms. Specific mono-olefins include decene-1, dodecene-1, octadecene-1, eicosene-1, tetracosene-1, and other straight or branched chain alpha-olefins which are amenable to isomerization in accordance with the present invention.

The olefin feed stocks may also be obtained from thermal or catalytic cracking of hydrocarbons such as gas oils, paraffinic waxes, petrolatums and the like or by polymerization of low molecular weight olefins. A convenient source of feed stock is the so-called "Fischer synthesis" process in which carbon monoxide is hydrogenated in the presence of metal oxides or other catalysts. For example, relatively high concentrations of alpha-olefins are sometimes found in Fischer synthesis products produced when using iron oxide catalysts. Products from these various operations may be distilled, solvent extracted, extractively distilled, and the like by conventional procedures to obtain feed stocks containing useful concentrations of the desired alpha-olefins.

The feed stocks may comprise in addition to alpha-olefins relatively high concentrations of paraffins, naphthenes, aromatics and other hydrocarbons boiling in the same or different boiling range. It is preferred of course that these extraneous hydrocarbons be substantially inert to reaction with or polymerization by the metal catalyst. For example, the feed stock should be substantially free or contain only very small concentrations of acetylenic or diolefinc hydrocarbons, sulfur and nitrogen compounds, water and the like. Such compounds may under the conditions employed polymerize or form sludge which tends to deactivate the catalyst and contaminate the reactants. Such undesirable compounds may be removed from feed stocks by conventional refinery methods such as by light acid treating, adsorption, and the like. Although the feed stocks may contain alpha-olefin concentrations as low as about 10% or so, it is desired that the stocks contain a major portion, preferably above 60 weight percent, of such olefins. Obviously the feed stock may also contain other types of olefins which may or may not be affected in the isomerization step.

The advantage of the present invention is demonstrated by the following specific examples of liquid phase isomerization runs:

EXAMPLE I

An olefin feed stock containing about 96 weight per cent C₁₁ to C₁₉ olefins and about 2 weight per cent diolefins was employed in this run. Sodium particles were added to the feed stock and the mixture was agitated at 120° C. in an Eppenbach homogenizer in order to make a dispersion comprising 2.1 weight per cent sodium, based on the olefins, the sodium particles having a size in the range of about 20 to 50 microns. The temperature of the dispersion was lowered and was then agitated for one hour at 93° C. The reactants were filtered through "Hi-flo" (a diatomaceous filter aid) and then through laboratory filter paper to recover a product substantially free of sodium and sludge.

EXAMPLE II

The feed stock of Example I was employed to make a dispersion containing 11.1% of sodium. The dispersion included 1.5 weight per cent carbon black and 1.5 weight per cent oleic acid, based on the sodium. A portion of

the resulting concentrate was added at substantially room temperature to another portion of the feed stock to form a mixture containing 1.0 weight per cent sodium based on the olefins. 10 mol per cent isopropyl alcohol, based on the sodium, was added to the mixture as an activator. The total mixture was then charged to a bomb actuated by a rocking mechanism and was agitated for 30 minutes at a temperature of 225° C. The product was cooled, removed from the bomb and filtered.

EXAMPLE III

The feed stock employed in this run comprised 100% octadecene olefins. A sodium dispersion was prepared by dispersing 11 weight per cent sodium in an aliphatic hydrocarbon distillate boiling in the range of about 310 to 390° F. Sufficient sodium concentrate was blended with the feed to obtain a mixture having 0.5 weight per cent sodium based on the octadecene-1 in the feed stock. 10 mol per cent isopropyl alcohol, based on the sodium was added to the mixture, the mixture was heated to 225° C. in a rocker bomb, and this temperature was maintained for 1/2 hour while agitating. The reactants were cooled to room temperature and were filtered through acid-treated contact clay to remove sodium and other solid materials. The total heating cycle was completed in 1.5 hours.

EXAMPLE IV

A feed stock having a boiling range of 220° to 269° F. and comprising chiefly C₈ alpha-olefins was prepared. A concentrate was prepared containing 23 weight per cent sodium dispersed in an aliphatic hydrocarbon distillate boiling in the range of 310° to 390° F. and containing 1.5 weight per cent carbon black and 1.5 weight per cent oleic acid based on the sodium. Sufficient concentrate was added to the feed to obtain a 0.5 weight per cent concentration of sodium based on the olefin. The mixture likewise contained 10 mol per cent of isopropyl alcohol based on the sodium. The mixture was agitated and heated at 225° C. for 1/2 hour, cooled and filtered.

EXAMPLE V

A run was carried out in the same manner of that described in Example IV except that the olefin feed stock had a boiling range of 170° to 220° F. and contained chiefly C₇ alpha-olefins. The reaction temperature was maintained at 200° C. for 1/2 hour.

The feed stocks to and the products from the above runs were analyzed by infra-red spectrographic analytical procedures. The analysis determined the concentration of Type I olefins (monosubstituted ethylenes), Type II olefins (symmetrically disubstituted ethylenes) and Type III olefins (unsymmetrically disubstituted ethylenes). The run conditions and analytical data for each of the examples is shown in Table I.

Table I

Example No.	I	II	III	IV	V
Olefin Feed stock used	C ₁₁ -C ₁₉	C ₁₁ -C ₁₉	C ₁₈	C ₈	C ₇
Sodium, Weight Percent Based on Olefins	2.1	1.0	0.5	0.5	0.5
Isopropyl Alcohol, Mol Percent Based on Sodium	0	10.0	10.0	10.0	10.0
Oleic Acid, Weight Percent Based on Sodium	0	1.5	0	1.5	1.5
Carbon Black, Weight Percent Based on Sodium	0	1.5	0	1.5	1.5
Run Conditions:					
Temperature, °C.	93-120	225	225	225	200
Contact Time, Hour	1.0	0.5	0.5	0.5	0.5
Olefin Type Analysis, Weight Percent:					
Feed Stock—					
Olefin, Type I (CH ₂ =CHR)	87	87	83.6	75.6	77.3
Olefin, Type II (RCH=CHR)	4	4	4.5	5.6	7.7
Olefin, Type III (CH ₂ =C-R)	5	5	11.9	14.5	6.5
R					
Product—					
Olefin, Type I	87	7	42.2	75.1	76.9
Olefin, Type II	4	80	40.0	5.4	7.6
Olefin, Type III	5	3	17.8	14.3	6.2

It is seen that substantial isomerization of Type I olefins did not occur at temperatures below about 120° C. On the other hand significant shifting of the double bond to form Type II olefins having in the range of 11 to 19 carbon atoms occurred at higher temperatures. The C₇ and C₈ olefins were not isomerized.

What is claimed is:

1. The process of isomerizing mono-olefin hydrocarbons having at least about 10 carbon atoms in the chain which comprises the step of contacting said olefin with alkali metal at an active isomerization temperature of at least about 150° C. whereby shifting of the double bond occurs.
2. A process for isomerizing terminally unsaturated mono-olefin having in the range of about 10 to about 25 carbon atoms which comprises the steps of intimately contacting said olefins with finely divided alkali metal at a temperature of at least about 150° C., and below the temperature at which substantial cracking of said olefins occur, separating metal from the reactants, and recovering a product including isomerized olefins.
3. A process as in claim 2 in which the alkali metal is sodium.
4. A process as in claim 2 in which the temperature is in the range of 175° to 425° C.
5. A process as in claim 2 in which the alkali metal is dispersed as finely divided molten particles in said olefin.
6. A process for isomerizing C₁₀ to C₂₅ mono-alpha olefins which includes the steps of contacting the olefins in the liquid phase with dispersed sodium particles at a temperature in the range of about 150° to 425° C., said sodium being present in an amount in the range of about 0.01 to 20.0% by weight based on said olefins, separating sodium from the reactants, and recovering a product including internally unsaturated olefins.
7. A process as in claim 6 wherein said sodium particles have diameters below about 100 microns.
8. A process as in claim 7 wherein said isomerization is carried out in the presence of about 1 to 30 mol percent, based on said sodium, of an oxy hydrocarbon activator having below about 10 carbon atoms.
9. A process as in claim 8 wherein said oxy hydrocarbon contains an active hydrogen.
10. A process for isomerizing C₁₁ to C₁₉ monosubstituted ethylenic hydrocarbons to internally unsaturated olefins which includes the steps of forming a mixture comprising said olefins dispersed sodium particles in an amount in the range of about 0.1 to 10% by weight based on said olefins, and a small amount of an alcohol having below about 10 carbon atoms, agitating said mixture in the liquid phase at a temperature in the range of about 175° to 350° C. for a time sufficient to cause substantial isomerization, and removing sodium and other undesirable materials from the resulting product.
11. A process as in claim 10 wherein said sodium particles have diameters below about 100 microns.
